HEDGE TRIMMER

William A. Batson, Pickens, S.C., assignor to The Singer
Company, New York, N.Y., a corporation of New Jersey

Filed Feb. 9, 1967, Ser. No. 5,752

Term of patent 14 years

(Cl. D40—1)

Fig.3.

Fig.2.

Fig.5.

Fig.4.

Fig.6.

Fig.7.

FIG. 1 is a perspective view of a hedge trimmer embodying my new design;

FIG. 2 is a top plan view thereof;

FIG. 3 is a left hand side elevational view thereof;

FIG. 4 is a right hand side elevational view thereof;

FIG. 5 is a bottom plan view thereof;

FIG. 6 is a front elevational view thereof; and

FIG. 7 is a rear elevational view thereof;

The dominant features of my design reside in the portions shown in the full lines.

The blade members illustrated in broken lines in FIG. 1 have been omitted in FIGS. 2-7 for convenience of illustration only.

I claim:

The ornamental design for a hedge trimmer, as shown and described.
